UNITED STATES PATENT OFFICE.

CASPER BUHRER, OF CAMBRIDGE CITY, INDIANA.

AUTOMATIC CONTINUOUS RAIL-FROG AND SWITCH.

SPECIFICATION forming part of Letters Patent No. 352,079, dated November 2, 1886.

Application filed March 26, 1886. Serial No. 196,713. (No model.)

To all whom it may concern:

Be it known that I, CASPER BUHRER, a resident of Cambridge City, Indiana, have made certain new and useful Improvements in Automatic Continuous Rail-Frogs and Switches, a description of which is set forth in the following specification, reference being made to the accompanying drawings, in the several figures of which like letters represent like parts.

My invention relates to the construction of automatic frog and switch connections for railway-tracks; and it consists in the construction, combination, and arrangement of the several parts hereinafter set forth, and will be understood from the following description.

In the drawings, Figure 1 represents a cross-section on the line *x x* in Fig. 3. Fig. 2 represents a cross-section on the line *y y*, Fig. 4. Fig. 3 is a top view of my device, showing the normal arrangement and position of the several parts. Fig. 4 is a similar view of my device as it appears when the pivoted bars are pressed downward by the pressure of the train and the wing-rail *w* is thrown up against and over the main rail, so that a train approaching from the siding would pass safely on over the main track to the continuation of the siding beyond. Fig. 5 is a side view of the outer siding-rail, showing the arrangement of the pivoted bars and their joints and connection with the crank-rod.

In detail, *m* is the main track, which is continuous throughout, and *s* is the side track, the outer rail of which is continuous throughout. The junction of the inner siding-rail with the main rail is formed by the frog *f*, which consists of a triangular piece of metal having an offset next the main rail and of the same depth, a central tongue, and an outer rail portion, a groove being left between the tongue and outer rail portion deep enough for the flange of the car-wheel to travel in in passing over the frog. This frog is substantially identical with the frog shown and described in another application filed contemporaneously herewith, and need not be further described here.

w is a wing-rail pivoted at *p*. Its outer end is curved, and through the other end of this rail is passed a bolt, on the outer end of which is coiled a spring, *sp*, adapted to be compressed between a washer on one end and a plate mounted on the bolt some distance be-

low. This frog-rail is connected by a connecting-rod, *c*, to the bend of the crank-rod *cr*. The object of this spring is to draw the wing-rail *w* back in the position shown in Fig. 3 after it has been drawn over in the manner shown in Fig. 4.

On the side of the outer siding-rail are pivoted bars *b* and *b'*, which extend along the side of the rail to within a short distance of each other, and these are connected by intermediate joints, *j* and *j'*, which are pivoted at 2 and 3 to the bars *b* and *b'*.

5 represents the pivot of the central knuckle-joint, and *l* and *l'* are lugs or plates, the faces of which abut against each other as the bars *b* and *b'* are pressed in, making flat bearings at the ends. The crank-rod *cr* has small upset ends or knees, which enter the bars *b* and *b'* at *k k'*, the whole being arranged in such a manner that when any weight or pressure is brought upon the top edge of the bar *b* or *b'* both the bars are forced downward, moving on the central pivot at 5, bringing the parts *l l'* together. 7c 75

The pressure on the knees *k k'* operates to turn the crank-rod, so that the crank *cr* is thrown outward, carrying the connecting-rod *c* with it, and drawing the wing-rail *w* up against and over the main rail in the position shown in Fig. 4. The bringing of this wing-rail over and against the main rail compresses the spring *sp*, as shown in Fig. 4, and when the pressure upon the bars *b* and *b'* ceases the spring exerts its force and draws the wing-rail back to the position shown in Fig. 3.

To illustrate further the operation of the device, the inner siding-rails, *s*, on both sides of the frog are elevated, so as to lift the wheel of a train approaching the main track from the siding over the level of the main-track rail, the highest point of elevation being about the center of the frog, and decreasing gradually to a level in either direction from that point. Thus if a train on the siding is approaching the main track, moving in the direction of the arrow in Fig. 4, it rises gradually until it reaches the frog, the flange of the wheel moving in the groove *gr*, and the bar *b'* is pressed down, carrying the connected bar *b* at the other end. The pressure is transmitted through the knees *k k'* to the crank, throwing the bend of the crank outward and drawing the wing-rail *w* over to the position shown in Fig. 4, and as 100

the tread of the wheel leaves the frog it passes at once to the top of the wing-rail *w*, and thence along the siding, safely over the main track. When the train has passed over, the pressure 5 upon the bars being released, the spring *sp* exerts its force, throwing back the wing-rail to the position shown in Fig. 3, leaving the main track clear for the passage of trains.

It makes no difference which direction the 10 trains come upon the siding, as the pressure upon either of the bars *b* or *b'* operates automatically to throw the wing-rail to form a passage for the car-wheel over the main track to the siding. When the pressure is removed, 15 the connection is again thrown open, leaving the main track clear.

If desired, the bars *b* and *b'*, instead of being placed on the outside of the rail, as shown in Fig. 5, may be placed on the inside of the siding-rail, and in that case it would be well to provide the bar with a groove, so that the flange of the car-wheel might enter that groove and be more certain to produce the pressure to operate the crank-rod and wing-rail. One method 20 is precisely the equivalent of the other, the only difference being a slight change in mechanical construction.

This automatic mechanism is as well adapted 25 for throwing a switch as for operating the wing-rail and frog-connection, and is arranged to operate in a similar manner. As the train comes upon the switch, if it is open, the pressure upon the bars connected with the crank-rod will operate to throw the switch-rail automatically in proper position, so that the train 30 may pass safely over the main track, and the release of that pressure will throw the switch-rail away, leaving the main track clear.

The relative elevation of the parts, as shown 35 in cross-section in Figs. 1 and 2, will doubtless be readily understood without further description.

What I claim, and desire to secure by Letters Patent, is the following:

40 1. An automatic continuous-rail mechanism composed of a curved wing-rail elevated above the main track and pivoted at one end along the side of such track, and connected to a crank-rod which is operated by one or more pressure-bars pivoted to the side of a switch or siding-rail, so that a train passing over such rail and bars will force said bars downward and operate the crank-rod, so as to throw the wing-rail in position for the siding or 45 switch, all combined substantially as described.

2. The main track *m*, the side track, *s*, the inner rail of the siding elevated above the main track near its junction, the frog-piece *f*, bolted to the main track, so as to complete the junction of the siding with such main track, the wing-rail *w*, pivoted at *p* and connected by a rod, *c*, to the crank-rod *cr*, the spring mechanism *sp*, secured to the wing-rail, the pressure-bars *b* and *b'*, pivoted to the outer siding-rail and connected together by the joints *j* and

j', and adapted to operate upon projections *l* and *l'* of the crank-rod *cr*, all combined substantially as described.

3. An automatic continuous-rail mechanism composed of a curved wing-rail elevated above the main track and pivoted at one end along the side of such track, connected to a crank-rod which is operated by one or more pressure-bars pivoted to one of the siding-rails, 70 so that a train passing over such rail will force said bars downward and operate the crank-rod, so as to throw the wing-rail in position for the siding or switch, the spring mechanism *sp*, connected with the wing-rail *w*, for drawing the wing-rail back from the main track, the elevated frog-piece for completing the junction between the siding and the main track, and the guide-rail *g*, all combined substantially as described.

4. An automatic continuous-rail mechanism composed of a main track, side-track rails, the inner one elevated above the main track, an elevated curved wing-rail pivoted at one end along the side of such track and connected to a crank-rod which is operated by one or more pressure-bars pivoted to one of the siding-rails, so that a train passing over such rail will force said bars downward and operate the crank-rod, throwing the wing-rail 90 in position for the siding or switch, and an elevated frog-piece bolted to the main track, completing the junction between the siding and main-track rail, all combined substantially as described.

5. A railway-track junction composed of main rails and siding-rails, the junction between the two formed by a frog, the tongue and track portion of which are elevated above the main rails, the siding-rails in either direction from such junction with the frog being also elevated above the main rail, decreasing from about the center each way to an ordinary level, a wing-rail pivoted to one side of the main-track rail and elevated above such rail, 100 adapted to be thrown in line with the siding-rails by means of the pressure of the car-wheel upon the top of bars pivoted to the outer siding-rail, connected by a suitable crank-rod mechanism with the wing-rail, and a spring mechanism for throwing the wing-rail away from the main-track rail when the pressure upon such bars is released, all combined substantially as described.

6. A track mechanism composed of a pair 110 of ordinary rails, one or more pressure-bars pivoted to one side of such rails, and a crank-rod connected to such pressure-bars, operated by the pressure of the car-wheel upon the top face of the pressure-bar, substantially as described.

In witness whereof I have hereunto set my hand this 18th day of March, 1886.

C. BUHRER.
